UNITED STATES PATENT OFFICE

2,649,799

PICTURE-FRAME ALBUM

Maurice Spertus, Highland Park, Ill.

Application August 19, 1950, Serial No. 180,461

6 Claims. (Cl. 40—152)

1

This invention relates to picture frames and to albums, and more particularly it relates to a combination picture frame and album which may be supported in an upright position on a surface or hung from a wall or the like.

Heretofore picture frames and albums have been afforded in numerous shapes and types but always as individual or separate devices. Hence pictures and photographs which were not being displayed in the picture-frame at the time had to be stored separately in albums and the like. Consequently it was necessary to afford additional storage space for the album; albums were often lost or mislaid and pictures and photographs were sometimes cracked, torn or injured.

It is therefore an important object of this invention to provide a unitary picture frame and album which will overcome the disadvantages set forth above.

Another important object is to afford a picture frame having a compartment for storing photographs or photograph albums.

A further object is to provide a picture-frame which does not look unlike the usual such frame with a supporting device such as an easel but which contains a hidden compartment and album.

Still another object is to provide a picture-frame album having means for storing a plurality of photographs therein. A related object is to so construct the picture-frame album that the displayed photograph may readily be removed and simultaneously another stored photograph exposed to view. Still another object relating thereto is to construct a picture-frame album in a manner which will permit replacement of the displayed or exposed photograph without necessitating even partial dismantling of the frame.

Still a further object is to provide a picture album with a picture-frame for displaying pictures and photographs. An object relating thereto is to utilize said picture-frame and displayed photograph as means for identifying the general subject matter of the contents of the album.

Yet another object is to afford a combination picture-frame and album which embodies all the desirable characteristics of both devices.

Yet a further object is to provide a picture-frame album capable of storing a plurality of pictures in consecutive displaying position; the device having means for removing or inserting the pictures without necessitating the opening or dismantling of the frame.

And still another object is to provide a picture-frame album of simple, inexpensive construction yet most effective and attractive.

2

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings, preferred embodiments thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a perspective view of my improved picture-frame album in operative position;

Fig. 2 is an enlarged perspective view as observed from a somewhat different angle;

Fig. 3 is a perspective view with the frame opened to reveal the inner compartment and album therein;

Fig. 4 is a perspective view similar to that of Fig. 3 but with the album also opened and illustrating the manner in which photographs may be inserted therein and removed therefrom;

Fig. 5 is a sectional view taken on the plane of line 5—5 in Fig. 2 and viewed in the direction indicated;

Fig. 6 is a sectional view showing in elevation another embodiment of my invention; and

Fig. 7 is a fragmentary perspective view of the same embodiment.

Reference numeral 10 indicates generally a picture frame album which may be supported in a vertically inclined position as by an easel 12. Hence the picture frame album does not look unlike an ordinary easel supported picture frame. However, upon closer examination, it will be noted that the album comprises two sections; a front section 14 and a rear section 16 pivotally connected along one side as by hinges 18, and provided on the other side with a locking device such as 20.

The front section 14 serves as the picture dis-

playing member and may comprise a channel shaped frame such as 22, which may be formed of any suitable material such as metal, wood, plastic, chemically treated pulp products and the like. The front of this frame 22 may be formed with an inwardly cambered flange such as 24 behind which may be positioned a sheet of transparent material such as a pane of glass 26. To the rear face of the front segment 28 of the channel 22 may be affixed a molding such as 30 which in cross-section may be Z-shaped thus affording a flange portion 32 which is spaced from the front segment 28 of the channel as shown in Fig. 5 of the drawings.

The channel 22 is formed with side segments such as 34 and rear segment 36 formed integrally at right angles to the plane of the side segment 34. A sheet of backing material such as cardboard 38 is positioned directly in front of the rear channel segment 36 and behind the molding flange 32. The photograph or picture to be displayed such as 40 may then be inserted directly behind the glass pane 26 and with its marginal edges in front of the molding flange 32. Central spacers such as 42 and 44 may be positioned between the photograph 40 and the backer 38 to retain the same in a flat unbent condition.

The rear section 16 may likewise be formed from a channel shaped frame such as 46 and in cross-section may comprise a rear segment 48 which, as shown in Fig. 5 of the drawings is disposed in a horizontal plane, a side section 50 integrally formed at right angles to the rear segment 48 and a front segment 52 which projects inwardly in a plane parallel to that of the rear segment 48 so that a compartment 54 is defined by said segments. Within said compartment may be stored a picture album such as 56 which may in turn comprise a pair of covers such as 58 and 60 with a plurality of picture storage compartments such as 62 all bound together in book form as by ring binders 64. This album 56 may be positioned and retained within the compartment 54 in a manner which will be revealed as the description proceeds.

The rear of the compartment 54 may be closed as by a backer 66 which may comprise a sheet of cardboard or the like positioned with its marginal edges affixed to the front of the rear segment 48 of the channel 46 as by glueing or the like. Affixed to the front of the backer 66 may be a member 68 in a manner to afford a pocket such as 70. A longitudinal slit such as 72 affords an entrance to the pocket 70 so that the rear cover 58 of the album 56 may be inserted therein; thereby positioning and securing the album within the compartment 54.

An easel 12 of the usual and ordinary construction may be affixed to the rear of the backer 66 as by glueing or in any other suitable manner.

As shown in Figs. 3 and 4 of the drawings, the picture frame album may readily be opened to reveal the compartment 54 and the album 56 contained therein. To lock the sections 14 and 16 together when the album is not being used, the locking device 20 is provided. This locking device may comprise a tongue 74 affixed to the side channel segment 50 as by a hinge 76 and formed with an opening 78 at the opposite end thereof. An outwardly projecting pin such as 80 may be affixed to the side segment 34 of the front channel 22 in aligned position with the opening 78 so that the pin 80 may cooperate with said opening to lock the two sections 14 and 16

together. This pin 80 may be inwardly tapered as shown in Fig. 5 so that it will not readily slip out of the tongue opening 78.

As shown in Fig. 4 of the drawings, the album 56 provides means for storing additional photographs such as 82 which may be inserted within the picture storage compartments 62. These compartments may be provided between sheets of transparent plastic and the like so that the pictures may readily be viewed. When desired the photograph such as 82 may be removed from the compartment 62 and substituted for the photograph 40 displayed in the picture frame section.

Figs. 6 and 7 illustrate a modification of the original embodiment in which a plurality of photographs may be stored in consecutive picture displaying positions, one behind the other; and the exhibited photograph may readily be replaced by other photographs without necessitating the opening of the picture-frame album or even the partial dismantling of the picture frame.

In this modification the album and picture frame may be unitarily formed. Hence a closed back housing is afforded comprising in cross-section a unitarily formed back member 90, side, top and bottom walls 92 and inwardly flanged front segments such as 94. The front segments 94 have their ends cambered to afford the inclined segments 96. The ends of such segments 96 are then bent to lie in a vertical plane as shown at 98. A large opening indicated generally by reference numeral 100 is framed by the flanges 98. Affixed to the front segments 94 is a molding 102 completely encircling the opening 100. This molding may be inwardly cambered as at 104 but terminates in spaced relationship with the flange 98. Disposed within the opening 100 may be a transparent member such as a pane of glass 106 positioned with its marginal edges securely retained between the molding 102 and the flange 98.

Positioned directly behind the flange 98 are a plurality of pictures or photographs such as 108 with the images facing the glass member 106. A backing member such as 110 is positioned directly behind the stack of photographs 108 and may be affixed to the front portion 112 of a leaf spring 114. This leaf spring may be positioned, and allowed to expand, between the back member 90 and the photographs 108, thereby retaining the photographs in picture-displaying position.

A slot 116 is provided in the top wall 92 aligned with the flange 98 so that a photograph such as 108 may be inserted in the slot 116 and pushed down, in the direction indicated by the arrow, in front of the other photographs so that the specific picture may be displayed directly behind the glass member 106. Similarly a slot 118 is provided in the bottom wall 92 and spaced from the front of the frame so that the rear photograph 108 may readily be removed from the album by moving the same downwardly in the direction indicated by the arrow. As the picture is removed, the leaf spring 114 expands to maintain the other photographs in the proper position.

To enable the user to readily remove the photographs through the bottom slot 118, an opening 120 is formed at the bottom of the back member 90 communicating directly with the slot 118 as shown in Figs. 7 and 8 of the drawings. A similar opening 122 is formed at the bottom of the backing 110 and is aligned with the opening

120. Thus to remove a photograph 108 from the rear of the picture stack, all that need be done is for the operator to insert his thumb into the slots 120 and 122 until the rear photograph 108 is frictionally engaged. The photograph is then pushed downwardly until the bottom portion protrudes through the slot 118 as shown in Fig. 6 of the drawings. The operator may then grasp this protruding portion and pull the photograph out of the album.

Completing the picture-frame album is a supporting device such as an easel 124.

It will thus be readily perceived that I have provided a combination picture frame and album which may be constructed in various types and styles to afford means for displaying a photograph and further means for storing photographs in the same device. I have further provided a combination picture frame and album in which photographs may be replaced without necessitating the opening of the album or even the partial dismantling of the frame. The advantages of this construction are too numerous to be individually set forth but it should be obvious that this device fulfills a long felt need.

It is believed that my invention, its mode of construction and assembly, and many of its advantages should be readily understood from the foregoing without further description, and it should also be manifest that while preferred embodiments of the invention have been shown and described for illustrative purpose, the structural details are nevertheless capable of wide variation within the purview of my invention as defined in the appended claims.

What I claim and desire to secure by Letters Patent of the United States is:

1. In a device of the character described, a picture frame adapted to display a photograph therein, another closed-back frame affording a compartment therein, both of said frames pivotally connected along one side, a locking device affixed to the opposite side, the rear wall of said compartment formed with a pocket therein and an album adapted to being positioned within said compartment with one cover positioned within said pocket.

2. A picture frame album of conventional appearance comprising a picture frame housing, said housing divided into two sections connected and hinged along one side, one section comprising a picture frame having a picture-displaying area, a molding frame encircling the marginal edges of said picture-displaying area, a glass pane positioned within said area and with the marginal edges thereof clamped between the frame and said molding, the other section comprising a picture album storage housing defined by integrally formed side walls and a back wall,

said back wall having a slot formed therein and a picture album having covers positioned in said second section, one of said covers positioned within said slot.

- 5 3. In a picture frame album comprising a picture frame housing, said housing comprising a plurality of sections pivotally connected along one side, at least one section including a picture frame having a picture-displaying area, a molding 10 frame encircling the marginal edges of said picture-displaying area, a glass pane positioned between said area and with the marginal edges thereof clamped between the frame and said molding, at least one other section comprising 15 a picture album storage housing including a back wall, said back wall having a slot whereby a cover of a picture album may be inserted therein.

4. A picture frame album comprising a picture frame housing, said housing comprising a plurality of sections pivotally connected along one 20 side, at least one of said outer sections containing a picture frame, and at least one of the other sections comprising a picture album storage housing having a back wall, said back wall 25 having a slot whereby a cover of a picture album may be inserted therein.

5. In a device of the character described, a picture frame adapted to display a photograph therein, another closed-back frame defining a compartment therein, both of said frames pivotally connected along one side, the rear wall of 30 said closed-back frame formed with a pocket therein and an album adapted to being positioned within said compartment with one cover positioned within said pocket.

6. In a device of the character described, a picture frame album having a front cover, said front cover including a picture frame for displaying a photograph, a closed-back housing defining a compartment therein, said front cover 40 and closed-back housing pivotally connected along one side, and the rear wall of said housing formed with a pocket whereby a cover of a picture album may be inserted therein.

MAURICE SPERTUS.
